HYDRAULIC JACK

Fred M. Siedenburg, Richmond Hill, N. Y.

Application May 12, 1947, Serial No. 138,995

Term of patent 3½ years

(Cl. D41—1)

To all whom it may concern:

Be it known that I, Fred M. Siedenburg, a citizen of the United States, residing at Richmond Hill, New York, in the county of Queens and State of New York, have invented a new, original, and ornamental Design for a Hydraulic Jack, of which the following is a specification, reference being had to the accompanying drawing, forming a part thereof.

In the drawing:

Fig. 1 is an elevational view of one side of a hydraulic jack, showing my new design;

Fig. 2 is an elevational view of the other side;

Fig. 3 is a front elevational view;

Fig. 4 is a top plan view; and

Fig. 5 is a bottom plan view of the same.

The dominant features of my design reside in the portions shown in full lines.

I claim:

The ornamental design for a hydraulic jack, as shown and described.

FRED M. SIEDENBURG.
